RADIO-FREQUENCY NETWORK

George H. Brown, Princeton, N. J., assignor to
Radio Corporation of America, a corporation
of Delaware

Application November 21, 1945, Serial No. 630,073

3 Claims. (Cl. 250—33)

1

This invention relates to radio frequency power networks wherein two independent sources, which must be electrically isolated from one another, are required to supply energy simultaneously to a common load device. Networks of the described type find application, for example, in television broadcast systems, wherein it is desired to transmit a picture signal and an accompanying sound signal from a single antenna. In order to prevent interchange of power between the sound and picture transmitters, it has been the practice to employ filters. Such filters require careful design, will operate only with sound and picture carrier frequencies for which they are designed, cause a certain amount of loss, and introduce reactances in the system which make it difficult to design the overall system for efficient broad band operation which is necessary for high definition television.

It is the principal object of the present invention to provide a radio frequency network which will substantially isolate two sources from each other, while enabling them to supply common loads simultaneously.

Another object is to provide a system of the described type which does not rely upon filters or equivalent means for the function of isolation, and thus introduces a minimum of undesirable reactance in the system.

Another object is to provide an isolation network coupling a single antenna system to a transmitter and another transmitter or a receiver for operation independently of one another.

A further object of this invention is to provide an isolation network which is readily adaptable to the requirements of combined sound and television broadcasting.

Still another object is to provide a network of the described type which is conveniently applicable to antennas of the type including two separately excited groups of radiators, such as the turnstile.

The invention will be described with reference to the accompanying drawings, of which Figure 1 is a schematic diagram of an isolation network according to the invention.

Figure 2 is a schematic diagram of a sound and television broadcast antenna system embodying an isolation network in accordance with the invention.

Refer to Figure 1. A pair of identical loads, represented by equal resistors 1 and 3, are to be energized simultaneously and independently from sources 5 and 7. The lower end of each

2

of the resistors is grounded; i. e. they are unsymmetrical or unbalanced to ground. The generators 5 and 7 are similarly unbalanced to ground. From a practical standpoint, this means that coaxial transmission lines may be used for the connections to the elements 1, 3, 5 and 7.

A coaxial line 9 is connected to the generator 5. A portion 10 at the end of the line 9 remote from the generator 5 is surrounded by a coaxial sleeve 11 of conductive material. The lower end of the sleeve 11 is connected to the outer conductor of the line 9 at their junction 13. The upper end portion of the outer conductor of the line section 10 is provided with a slot 15 extending diametrically across the line and longitudinally down to the point 17. The upper end of the inner conductor is connected to that of the outer conductor at one side of the slot 15.

The loads 1 and 3 are connected to the end 20 of the outer conductor of the line section 10, on opposite sides of the slot 15. The generator 7 is connected to the outer conductor of the line section 10 at a point 19 below the bottom 17 of the slot 15.

25 The operation of the system of Figure 1 is as follows:

The slot 15 extends longitudinally down the line section 10 one-quarter wavelength at the mean frequency of operation of the system.

30 When current at said frequency is supplied to the line 9 by the generator 5, the instantaneous current flow is up the inner conductor of the line 9 to the upper end of the outer conductor, at the right hand side of the slot 15.

35 The two parts of the outer conductor separated by the slot 15 cooperate to act as a quarter wavelength open wire line, short-circuited at the point 17. This presents a substantially infinite impedance between the upper ends of the two

40 portions of outer conductor and effectively prevents any of the current from the inner conductor from flowing down the outer conductor. Thus if a current I is flowing up the line 9 from the generator 5, the same current I flows into

45 the load 3.

The current I flowing up the inner conductor of the line 9 is balanced by an equal current returning down the inside of the outer conductor of the line 9. This current flows up through 50 the load 1 to the upper end of the outer conductor of the line section 10, at the left hand side of the slot 15. Owing to the high impedance across the upper end of the slot, all of this current flows down inside the left hand portion of 55 the outer conductor, spreading over the interior

surface of the outer conductor of the line section 19 below the slot 15. Thus the two loads 1 and 3 are energized in phase opposition or push-pull by the generator 5.

At frequencies other than that at which the slot 15 is exactly one-quarter wavelength long, some of the current flowing up the inner conductor line 9 flows down the inside of the right hand portion of the outer conductor. This induces a current upward in the left hand portion, reducing the total current which flows from the load 1 to its point of connection. Thus the currents to the two loads remain equal to each other, but they are no longer the same as that flowing up the line 9. The net effect is somewhat similar to that of shunting the generator by the reactance of the parallel wire line section formed by the two end portions of the outer conductor of the section 10.

The outer conductor of the line section 10 operates with the sleeve 11 to function as a coaxial line section short-circuited at its lower end 13. Current from the generator 7 is applied to this line section at the point 19. This current induces a voltage along the outside of the outer conductor of the section 10 by autotransformer action. The voltage to ground from both arms of the outer conductor is the same. Thus the voltage between the ends of the outer conductor is zero, and no current is induced in the line 9 by the generator 7.

Since the two ends of the outer conductor are at the same voltage with respect to ground, equal currents flow from them through the load resistors 1 and 3. These currents are in phase with each other, as indicated by the dash arrows. None of the current from the generator 5 flows on the outside of the outer conductor of the line section 10, so no current is induced in the generator 7 by the generator 5. Thus both loads are energized by each generator, without interaction.

The above described system may be applied to advantage in a combined television and sound transmission system wherein a single antenna system is used. Referring to Figure 2, an antenna of the turnstile type, comprising four orthogonally disposed radiator arms N, S, E and W, is to be energized simultaneously by a sound transmitter 21 and a picture transmitter 23. The radiator pair N-S is to be excited as a dipole, and the other pair E-W as another dipole in quadrature phase with respect to the first. In Figure 2 all coaxial lines are represented as single lines, whose connections correspond to those of the inner conductors of the actual coaxial lines. All of the outer conductors are connected together and grounded.

The radiators N and S are connected together by a line 25. A feed line 27 is connected to the line 25 at a point 29 one-quarter wavelength from the midpoint of the line 25, so that the distance from the point 29 to the radiator N is one-half wavelength different from the distance between the point 29 and the radiator S. The radiators E and W are similarly connected together by a line 31, tapped one-quarter wave off center at the point 33, where a second feed line 35 is connected.

The line 27 is one-quarter wavelength longer than the line 35. The lines 27 and 35 are connected like the loads 1 and 3 in the system of Figure 1 to a network 37, identical with the structure shown in Figure 1. The picture transmitter 23 is connected to the network 37 like the genera-

tor 5 of Figure 1, and the sound transmitter 21 is connected like the generator 7 of Figure 1.

In the operation of the system of Figure 2, the feed lines 27 and 35 are supplied like the loads 5 and 3 in Figure 1, out of phase by the transmitter 23 and in phase by the transmitter 21. Energy travels up the line 27 to the point 29. From this point, it reaches the radiator S over a path one-half wavelength longer than the path to the radiator N. Thus current flows in on the radiator S while current is flowing out on the radiator N, and vice versa, exciting the radiators N and S as elements of a dipole.

The radiator elements E and W are excited similarly by energy flowing up the line 35. Since the line 27 is one-quarter wavelength longer than the line 35, the currents in the dipole N-S are in quadrature phase with the corresponding currents in the dipole E-W.

The effect of feeding the lines 27 and 35 in push-pull from the transmitter 23 and in the same phase from the transmitter 21 is merely to cause the phase rotation of the turnstile to be in one direction (e. g. clockwise) for the output of the sound transmitter and in the opposite direction for the picture signal.

Although a relatively simple antenna system has been illustrated to show a typical application of the present invention, it will be understood by those skilled in the art that it is not restricted thereto, but may be applied equally well to any system wherein separate load elements are to be excited simultaneously by two sources without interaction.

I claim as my invention:

1. An antenna system including an isolation network comprising a first coaxial input line, a conductive sleeve surrounding one end of said line and connected to the outer conductor of said line at a point near said end, the end portion of the outer conductor of said line including a longitudinal slot, the end of the inner conductor of said line being connected to the end of the outer conductor of said line at one side only of said slot, a second coaxial input line with its outer conductor connected to said sleeve and its inner conductor coupled to the outer conductor of said first input line within said sleeve, and a pair of coaxial output lines with their outer conductors connected to said sleeve and their inner conductors connected to the end of the outer conductor of said first input line on opposite sides respectively of said slot, dipole radiator means coupled to one of said output lines, and further dipole radiator means at right angles to said first radiator means and coupled to the other of said output lines, one of said output lines being one-quarter wavelength longer than the other.

2. An isolation network for radio frequency power systems including a first coaxial input line, a conductive sleeve surrounding one end of said line and connected to the outer conductor of said line at a point near said end, the end portion of the outer conductor of said line including a longitudinal slot, the end of the inner conductor of said line being connected to the end of the outer conductor of said line at one side only of said slot, a second coaxial input line with its outer conductor connected to said sleeve and its inner conductor coupled to the outer conductor of said first input line within said sleeve, and a pair of coaxial output lines with their outer conductors connected to said sleeve and their inner conductors connected to the end of the outer conductor of said

first input line on opposite sides respectively of said slot.

3. An isolation network for radio frequency power systems including a first coaxial input line, a conductive sleeve surrounding one end of said line and connected to the outer conductor of said line at a point near said end, the end portion of the outer conductor of said line including a longitudinal slot, the end of the inner conductor of said line being connected to the end of the outer conductor of said line at one side only of said slot, a second input line with one conductor connected to said sleeve and the other conductor coupled to the outer conductor of said first input line within

5
said sleeve, and a pair of loads, each connected between said sleeve and the end of the outer conductor of said first input line, on opposite sides respectively of said slot.
